VERTICAL BAR OR THE LIKE

David P. Zagaroli, 2035 11th Street Court NW.,
Hickory, N.C. 28601

Filed Apr. 16, 1975, Ser. No. 568,509

Term of patent 14 years

Int. Cl. D6—04

U.S. Cl. D6—144

The figure is a front perspective view of the vertical bar or the like showing my new design.

The opposite side of the bar is substantially a mirror image of that shown.

The back and bottom of the bar are substantially plain and unornamented.

I claim:

The ornamental design for a vertical bar or the like, as shown and described.
